US0D1011447S

(12) **United States Design Patent** (10) **Patent No.:** **US D1,011,447 S**
(45) **Date of Patent:** **** Jan. 16, 2024**

(54) **WEIGHT LIFTING BELT**

(71) Applicant: **Nanjing Shangqiu Information Technology Co., Ltd**, Nanjing (CN)

(72) Inventor: **Liangyan Xie**, Nanjing (CN)

(73) Assignee: **Nanjing Shangqiu Information Technology Co., Ltd**, Nanjing (CN)

(**) Term: **15 Years**

(21) Appl. No.: **29/878,052**

(22) Filed: **Jun. 15, 2023**

(51) LOC (14) Cl. **21-02**

(52) U.S. Cl.

USPC **D21/662**

(58) **Field of Classification Search**

USPC ..... D21/662, 694, 684, 685, 686, 683, 679, D21/673; D29/121.1, 124, 101.2; D24/190; 482/139, 112, 105, 93, 92 CPC A63B 21/065; A63B 21/4009; A63B 21/4001; A63B 21/4025

Primary Examiner — Ryan Harvey

(57) **CLAIM**

The ornamental design for a weight lifting belt, as shown and described.

DESCRIPTION

FIG. 1 is a top, front, left side perspective view of a weight lifting belt showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown on the weight lifting belt depict stitching that form no part of the claimed design.

1 Claim, 8 Drawing Sheets
